(57) **CLAIM**

The ornamental design for an applicator, as shown and described.

DESCRIPTION

FIG. 1 is a left side elevational view of an applicator, showing our new design, wherein a right side is a mirror image of the left side;

FIG. 2 is a left side perspective view thereof;

FIG. 3 is a left side elevational view thereof, with the push rod partially removed;

FIG. 4 is a left side elevational view thereof, with the push rod removed from the applicator;

FIG. 5 is a rear elevational view thereof; and,

FIG. 6 is a bottom plan view thereof, with the push rod removed from the applicator.
